UNITED STATES PATENT OFFICE

JOHN WILLARD PETERSON, OF SIOUX CITY, IOWA

SHAVING MUG

Application filed June 25, 1930. Serial No. 463,691.

My invention relates to shaving mugs and has for its object to provide a device which is particularly adapted for use by a traveling salesman in small country hotels where hot water is not regularly furnished.

5 An object of my invention is to provide a shaving mug adapted not only to hold a cake of soap but also to heat a body of water within the mug in which the soap is immersed.

10 A further object of the invention is to provide a construction which is adapted to do this without undue dissolution of the cake of soap.

Another object of my invention is to provide a construction which is particularly 15 adaptable for use in a home.

It is my purpose in this connection to provide a bracket structure for supporting the shaving mug while it is being heated and for 20 supporting it while it is not in use. My invention in this respect further contemplates the attachment of the mug to the bracket in such a way that the mug may be removed from the bracket and supported independently of the bracket.

Another object is to provide a shaving mug including a soap holding cup that is removable, whereby the cup may be handled for the purpose of applying water to the soap 25 without the necessity of handling the entire mug.

With these and other objects in view, my invention consists in the construction, arrangement and combination of the various 30 parts of my device, whereby the objects contemplated are attained, as hereinafter more fully set forth, pointed out in my claims, and illustrated in the accompanying drawings, in which:

40 Fig. 1 is a plan view of my invention attached to a supporting wall.

Fig. 2 is a vertical, sectional view through the same.

Fig. 3 is a perspective view of the bottom 45 of the mug.

I have used the reference character 10 to indicate generally a supporting wall to which my invention may be attached, such as the wall of the bath room. To the wall 10 is 50 attached a bracket sleeve 11, which has a

vertical, cylindrical bore. The other half of the bracket is comprised in an arm having the vertical shank 12 which is journaled in the bearing bracket 11, a laterally projecting portion 13 and an upwardly projecting portion 14 to support the mug.

The shank 12 is provided with a reduced portion 15 which is received in a bushing 16 which in turn extends through the bore of the bearing bracket 11. The lower end of the shank 12 is threaded to receive a nut 17 which is locked tightly against the bushing 16 and which serves to secure the shank in the bearing bracket 11.

The end of the bracket arm portion 14 is provided with a reduced, threaded nipple 18 and a cup 19 provided with a central opening is supported on the shoulder thus formed and receives the nipple 18. A nut 20 secures the cup in place.

70 The shaving mug proper comprises a cylindrical casing wall 21 provided with an upper, inturned flange 22.

The bottom 23 is provided with down-turned tongues 24 which are secured to the wall 21 and legs 25 of insulating material such as fibre or the like are secured to the wall 21 and project somewhat below the lower edge thereof to support the mug on the bottom of the cup 19.

75 The flange of the cup 19 engages the wall 21 to give lateral support to the mug.

The legs 25 and the rivets 26 by means of which the legs 25 and tongues 24 are secured serve to space the mug from the cup 19 so as to minimize heat transfer between the two.

80 Supported on the bottom 23 is a disc of asbestos 27 to which is cemented a heating element support 28 of refractory material. A heating element 30 is mounted in the support 28. A liner of asbestos 31 is secured to the inner surface of the wall 21 and is extended down to meet the disc 27 of asbestos.

85 The upper edge of the liner is concealed by the flange 22 which also serves to hold the liner securely against the disc 27. Members 32 are connections to fit an electrical extension cord plug and are connected to the heating element 30.

90 A lower sheet of asbestos 45 is secured in

place by tongues 46 struck from the metal of the bottom 23. The asbestos sheet 45 is secured in place by tongues 46 struck from the metal of the bottom 23. The asbestos sheet 5 45 serves not only to aid in retaining the heat within the mug but also to cover the bottom of the mug against any exposure of the metallic bottom 23 in order that the operator may lift the mug by placing his fingers therebeneath should he desire to do so without the danger of burning his fingers. The asbestos sheet 45 also serves to prevent the heat radiating downwardly to a supporting surface such as a varnished table or the like.

10 15 In this connection it may be stated that the primary function of the legs 25 is to support the mug on a finished surface and to protect the surface against the transfer of heat by conduction.

20 25 The heating element support 28 is provided in its lower region with a cavity 47 which together with the asbestos disc 27 forms a dead air space to arrest the transfer of heat downwardly through the bottom of the mug.

25 30 35 The soap container or cup 33 is provided with an outwardly flanged rim 34 to rest on the flange 22 of the casing and snugly fits within the opening defined by the flange 22. A handle 35 is secured to the cup by means of a narrow, handle bracket 36, the construction of which and the method of attachment of which is obvious from the drawings. The soap tray 37 is formed of a piece of sheet metal and legs 38 are struck downwardly from the rim thereof. The legs 38 space the tray from the bottom of the cup 33. A handle 39 is secured to the tray 37 by means of rivets 40, the upper ends of which are pointed and project upwardly to engage a cake of soap 40 and secure it to the tray.

The upper end of the handle 39 is provided with a hook 41 which extends downwardly over the wall 21, thereby serving to position the soap tray accurately in the center of the cup. The cup is of larger diameter than the usual cake of shaving soap and by positioning the tray in the center of the cup a space will be left between the side of the cake and the lateral wall of the cup, allowing circulation 45 50 of water around the cake.

55 When the device is not in use the mug is supported by the bracket arm 13, which may be swung laterally to a position closely adjacent and parallel to the wall to which the bracket is secured, thereby positioning the mug out of the way.

When the mug is to be used, the bracket arm is pulled outwardly to a position where the mug is convenient to the operator; the cup is removed from the mug, the cup partially filled with water; the cup then replaced in the mug and the extension cord from an electric service outlet is attached.

60 Between the side wall 33 of the cup and the asbestos liner 31 is formed a cylindrical side

air space 48 and between the bottom of the cup and the heating element is formed an air space 49. The purpose of these air spaces is to provide for distribution of the heat from the heating element around the cup.

65 The heat produced by the heating element 30 will warm the air in the air space between the casing and the cup and the water within the cup will be warmed uniformly.

70 75 The liner 31 serves to prevent heat transfer laterally through the side wall of the mug and thereby retains the concentrated heat in the air spaces 48 and 49.

80 85 It may be noted that the liner 31 is secured in place at its lower extremity by the heating element support 28. It may be further noted that the liner in conjunction with the bottom disc 27 completely insulates the member 28 from the metal walls of the mug.

85 90 95 The soap may be taken out of the cup while the water is being warmed and then placed in the cup after the water has been warmed. The amount of water in the cup will be just sufficient to reach the top of the cake of soap when the latter is inserted and the operator may then work up a lather by simply rubbing his brush across the upper surface of the cake of soap. If there is too much water, the operator may lift the soap tray slightly while he is working up the lather. After the shaving is finished, the operator removes the cake of soap from the cup, pours out the water, rinses the parts, and returns them to their assembled condition. The mug may then be swung against the wall out of the way.

100 105 Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

110 115 120 125 1. In a shaving apparatus, a mug comprising a casing, an asbestos lining in said casing including a side liner and a bottom disc, a heating element support comprising a disc of refractory material supported upon said bottom disc and snugly fitting within the side liner, a soap receptacle supported in the casing above said heating element support and a heating element carried by said support and spaced from the bottom of the receptacle by an air space.

120 125 130 135 2. In a shaving apparatus, a mug comprising a casing, an asbestos lining in said casing including a side liner and a bottom disc, a heating element support comprising a disc of refractory material supported upon said bottom disc and snugly fitting within the side liner, a soap receptacle supported in the casing above said heating element support and a heating element carried by said support and spaced from the bottom of the receptacle by an air space.

an air space, the sides of the receptacle being spaced from the side liner of the casing.

3. In a shaving apparatus, a mug comprising a casing having side walls and a bottom, the upper extremity of the casing being provided with an inturned flange, a cup having an out-turned flange supported on said inturned flange received within the casing and spaced from the side wall thereof, a supporting block of refractory material carried by the bottom of the casing and spaced from the bottom of the cup and a heating element carried by said supporting block exposed to the space thereabove.

15 4. In a shaving apparatus, a mug comprising a casing, a heating element in the bottom of the casing, a cup supported from the top of the casing and spaced from said heating element and positioned to receive heat from said heating element and a soap tray comprising a tray proper and a handle extending upwardly therefrom and provided with a hook to engage the outer side and the inner side of the cup whereby to position the

25 soap tray centrally of the cup.

Signed this 28th day of May, 1930, in the county of Woodbury and State of Iowa.

J. WILLARD PETERSON.
